CLAIM

The ornamental design for a handheld current sensor, as shown and described.

DESCRIPTION

FIG. 1 is a front-left-top perspective view of a handheld current sensor showing the new design.

FIG. 2 is a front view of the handheld current sensor of FIG. 1.

FIG. 3 is a rear view of the handheld current sensor of FIG. 1.

FIG. 4 is a right side view of the handheld current sensor of FIG. 1.

FIG. 5 is a left side view of the handheld current sensor of FIG. 1.

FIG. 6 is a top view of the handheld current sensor of FIG. 1; and,

FIG. 7 is a bottom view of the handheld current sensor of FIG. 1.

The broken lines shown are included for the purpose of illustrating portions of the handheld current sensor that form no part of the claim.
